SPIKE CLEANER FOR GOLF SHOES OR THE LIKE

Virgil L. Elliott, 802 Ash St., Blackwell, Okla.

Filed Aug. 3, 1961, Ser. No. 66,236

Term of patent 14 years

(Cl. D9—2)

FIG.1

FIG. 3

FIG. 1 is a perspective view of a spike cleaner for golf shoes or the like embodying my new design;

FIG. 2 is a perspective view thereof, taken from the end opposite that shown in FIG. 1; and

FIG. 3 is an end elevational view thereof, taken from the left of FIG. 1.

I claim:

The ornamental design for a spike cleaner for golf shoes or the like, as shown.
